UNITED STATES PATENT OFFICE.

OSCAR W. SCHLAG, HENRY H. BURDORF, AND EDWARD H. SCHLAG, OF CHICAGO,
ILLINOIS.

RAILWAY SIGNALING SYSTEM.

1,125,736.

Specification of Letters Patent.

Patented Jan. 19, 1915.

Application filed April 21, 1911. Serial No. 623,639.

To all whom it may concern:

Be it known that we, OSCAR W. SCHLAG, HENRY H. BURDORF, and EDWARD H. SCHLAG, citizens of the United States of America, residing at Chicago, in the county of Cook and State of Illinois, have invented new and useful Improvements in Railway Signaling Systems, of which the following is a specification.

10 This invention relates to improvements in railway signaling systems.

The leading feature of my invention consists in providing a simple, effective, and inexpensive device of the character described 15 which consists of suitable electrically controlled mechanism for electrically communicating to a signal station the fact that a track is defective, or that a wash-out or bridge wreck or any other calamity has happened along any track.

With the above and other objects in view our invention consists in the combination, arrangement, and details of construction disclosed in the drawings and specification, 25 and then more specifically pointed out in the present claim.

In the drawings wherein similar reference characters designate similar parts:—Figure 1 is a top plan view of a railroad crossing 30 equipped with that part of the system relating thereto. Fig. 2 is a perspective view showing a wrecked bridge and disrupted track circuit. Fig. 3 is a perspective view showing a track washed out and a disrupted 35 track circuit. Fig. 4 is a longitudinal sectional view through one pair of spring jacks and plugs employed in the system, and Fig. 5 is a sectional view of one of the jacks showing the dummy plug used in connection 40 therewith at the end of a train or at the end of a line of rails.

Referring to the drawings by numerals there is disclosed the details of construction of our invention. In carrying out our rail-way system into practice we employ what 45 may be termed a main circuit. The main circuit of the system is preferably normally open and includes a conductor 10 arranged alongside of one of the lines of rails of the 50 trackway and suitably spaced apart therefrom and supported in any suitable manner. The other side of this same circuit is formed of one of the lines of rails of the track as the line 5, and leading from the conductor 10 55 and the line of rails 5 are lead wires 11 and

12 respectively terminating in a signal house S conveniently located with respect to the track way and equipped with suitable signals and signaling instruments, such, for example as telephones, telegraph instruments 60 and the like.

In order to bridge the conductors 5 and 10 of the main circuit and cut the line of rail 5 into said circuit and especially when a rail is dislocated or a washout or bridge wreck 65 occurs so that the main circuit to the signal station may be closed by way of the conductors 10 and 5, and the fact of this calamity thereby communicated, the meeting ends of the rails forming the lines 5 and 6 are 70 equipped with devices which, in the normal running condition of the track maintain an open circuit while when a rupture or defect occurs so that the rail is dislocated such circuit is bridged across the rupture. 75

To this end, we employ, in the present instance, pairs of spring jacks and plugs co-operative therewith to normally maintain an open circuit. These jacks and plugs are more especially illustrated in Figs. 4 and 5 80 wherein each jack and plug is shown as including a body 14 formed with a socket 15 in which are located the jack springs 16. Each body 14 has passed therethrough adjacent to the socket 15 therein, a shank 17 one 85 end of which is projected outwardly of the body and carries a number of balls 18, the latter being constructed of insulating material and appropriately spaced apart upon the shank and fastened thereto in any suitable manner or by any well known means. In the present instance each shank is provided with two pairs of contacting springs one spring of one pair being electrically connected to a spring of the other pair by means 90 of a strip 19, while the main springs of the pairs are electrically connected to the respective shanks 17 of the plugs and to the body 14, respectively. Thus, it will be seen that when the individual jack and plug of 100 the pairs are assembled, the plug carried by the body of one jack will hold the springs of the adjacent jack spaced apart and out of contact. The electrically connected contact spring of one jack and the free end of the 105 shank 17 of the other jack of the respective pairs are equipped with suitable binding posts to which are fastened conductors 20 and 21 terminally connected to the conductor 10 of the main circuit and forming a 110

bypath for the current. The shank 17 of the plug of the first named jack and the strip 19 on the second named jack are electrically connected through the respective rails of the line 5 at the opposite sides of the joint of said rails. At the ends of the line of rails, the springs of the signal jacks are held in spaced apart relation by means of a dummy plug 22 which may be constructed of wood, rubber, or any other suitable insulating material.

To carry out the purposes of our invention it is not necessary to provide both of the jacks 14 with the spring arrangement shown although the same has been illustrated as they control two circuits which are independent of each other one of the circuits described hereinafter operating the alarm in the signal station and the other circuit adapted to operate an alarm in the train which will not herein be described. Therefore the wire 21 may also be dispensed with as forming no part of our present invention.

The mode of operation of my invention will be as follows. Should any of the rails be dislocated or moved relatively to the adjacent rails, the plug will be moved out of engagement with the jack springs whereby the main circuit will be bridged and closed to the signal station. From Figs. 4 and 5 it will have been seen that each of the plugs is substantially provided with wedge shaped members arranged to enter the socketed portions of the plug to separate the spring contacts, said wedge shaped members taking the form of a plurality of balls which are mounted upon the projecting portion of each shank, and said balls decrease in diameter toward the extremities of said shanks. The spring contacts which are arranged in each socketed portion and which form separable ball receiving pockets, may thus be caused to contact when the plugs are disengaged, or to be separated when the balls of each shank are arranged to enter the adjacent socketed portion to engage the pockets and to separate said contacts. Therefore, when the rails

shall have been separated, and the balls shall have been disengaged from the spring contacts mounted in said plug, the relative position of the parts of each spring contact will be clearly illustrated in Fig. 5 and there will be a closed circuit to the signal station. Current may then flow from one side of the battery in the signal station to the conductor 10, thence to wire 20 and thence said current will flow to one of the closed spring jacks 16, and from the latter to the rail 5, and from the rail 5 the current will flow through the wire 11 back to the battery thereby closing the circuit and operating the alarm.

Numerous modifications may be resorted to in practice without departing in principle from the details of construction herein disclosed.

We claim—

In combination with the rails of a track, a line wire disposed alongside one line of said rails, a pair of jacks connected to each rail of said line of rails at one end of the rail joint, a shank carried by each jack, a plurality of spherical contact separating members mounted on each shank and projecting from either socket member, a plurality of normally interengaged contacts mounted in each jack to be separated when said spherical members are inserted thereinto a battery, a wire leading from one side of said battery to one of said rails, a wire leading from the opposite side of said battery to said line wire, a wire connecting said line wire and the interengaged contact of one of said jacks, and a wire engaging the shank in said last mentioned jack and said rail leading to said battery whereby a circuit is established when said operative contacts are interengaged.
